ELECTRICAL TUNING SYSTEM

George S. Wachtman, Harrisburg, Pa.

Original application October 5, 1943, Serial No. 505,048. Divided and this application November 14, 1944, Serial No. 563,384

3 Claims. (Cl. 250—40)

My invention relates broadly to circuit arrangements for high frequency oscillators and more particularly to a circuit for controlling the resonant frequency of tunable circuits over a variable frequency range with a high degree of precision.

This application is a division of my application Serial Number 505,048 for Electron tube apparatus, filed October 5, 1943.

One of the objects of my invention is to provide an improved circuit arrangement for controlling the resonant frequency of electrically tunable circuits with a high degree of precision.

Another object of my invention is to provide a multiple dual condenser controlled variable frequency oscillator circuit including series connected adjustable means for compensating for the effectiveness of the respective portions of the dual condensers at any point in the frequency range of the oscillator circuit.

Still another object of my invention is to provide a circuit arrangement for capacitively coupling a pair of dual condensers having sections having capacities which vary simultaneously in the same direction into an oscillator circuit for the precision control of the oscillation frequency.

Other and further objects of my invention reside in the improved multiple dual condenser circuit arrangement for electrical tuning systems as set forth in the following specification and shown in the accompanying drawing in which:

Figure 1 diagrammatically shows the circuit of my invention; Fig. 2 shows a modified form of circuit arrangement embodying my invention in which greater precision may be obtained in frequency adjustment of the circuit; Fig. 3 shows the ideal characteristic curves to be obtained by the circuit of my invention; Fig. 4 illustrates the actual characteristics obtained by the circuit arrangement of my invention without the corrective features added in accordance with my invention; and Fig. 5 illustrates the characteristic curves of the circuit of my invention with the compensation system of my invention added.

Referring to the drawing in detail Figure 1 schematically illustrates a circuit arrangement embodying my invention by which both high and low frequency compensation is secured in the tuning system. Reference character 1 designates the broad tuning condenser for the circuit and reference character 2 designates the dual or split stator fine tuning condenser electrically connected with the impedance 3 as shown. The dual condenser 2 includes two sections designated at 2a and 2b which are ganged together so that

their capacities vary simultaneously in the same direction. There is a single intermediate rotor and two stators associated with the intermediate rotor and variable in positions so that the effective capacities of the two condensers thus established vary simultaneously and in the same direction. Reference characters 5 and 7 designate variable trimmer condensers connected in series with sections 2a and 2b of the dual condenser 2 and connected to tap 3a on impedance 3 and to one side of the main tuning condenser 1. By adjustment of condensers 5 and 7 the control action of the fine tuning dual condenser 2 may be adjusted. A variable condenser 8 connects between one side of main condenser 1 and one terminal of impedance 3 whereby the minimum or lowest tunable frequency to which the circuit will respond may be adjusted.

In the operation of the circuit as thus far described it is possible with values assigned as follows to cover frequency ranges hereinafter explained with a high degree of precision:

Variable condenser 1—325 micro-microfarads
Split stator variable
25 condenser 2—Each section 25 micro-microfarads
Trimmer condenser 5—5-50 micro-microfarads
Trimmer condenser 7—5-50 micro-microfarads
30 Fixed condenser 8—70 micro-microfarads
Inductance 3—8.5 microhenries—20 turns 1.5" in diameter
x 1.375" long tapped
1/3 the distance from
the grounded end

35 By associating the elements as heretofore explained with an oscillator system, the frequency of the circuit may be continuously varied from 5,400 kcs./sec. to 9,200 kcs./sec. by varying condenser 1 and is also variable over a 100 kcs./sec. range by varying condenser 2 regardless of the setting of condenser 1. 2a and 2b are the two sections of the dual section, ganged variable condenser 2 controlled by one dial or knob, or other control constituting a bandspread control. The range covered by the bandspread control may be varied by adjusting trimmer condensers 5 and 7. Condenser 5 controls the amount of spread at the lower frequencies while trimmer condenser 7 controls the spread at the higher frequencies. The control action exerted by both is approximately equal at mid-frequency. Condenser 31 is a dual condenser whose two sections are ganged together so that their capacities vary simultaneously in the same direction, by means of which high and

low frequency compensation is obtained. The second dual condenser or compensation control 31 is similar to the first mentioned dual condenser 2 in that the two sections of the second dual condenser operates in such a way that the capacities of the two sections of the second vary simultaneously in the same direction much the same as the capacities vary in the first, although not necessarily in unison with the first.

The capacity of condenser 8 directly affects the 10 range covered or tuned by condenser 1, more capacity increasing the range and less capacity decreasing the range.

Fig. 2 discloses a modified form of the circuit of my invention for obtaining greater precision in 15 bandspread control. In this arrangement the parts of the circuit as described in Fig. 1 are employed with the addition of variable condensers 44 and 45, interposed in series between the dual control condenser 2 and the dual control condenser 37. The function of condensers 44 and 45 is to adjust the amount of control condenser 37 exerts with respect to dual condenser 2. By 20 independently adjusting condensers 44 and 45 a greater precision adjustment of the electrically tunable circuit is secured.

The two condenser sections 2a and 2b of the bandspread control condenser 2 always exert some control over the resonant frequency of the circuit regardless of the setting of main tuning control 1. Accordingly, the ideal control characteristics as set forth in Fig. 3 for each section of the condenser 2 are never realized. Instead some resultant characteristic which is non-linear is obtained as, for example, curves A' and B' of 30 Fig. 4 actually obtain for the circuit of Fig. 1 before the addition of dual condenser 31, curve C' being the resultant. Consequently some means of compensating for the non-linearity of curve C', Fig. 4, must be employed if accurate work is 35 to be done with the circuit. This is accomplished by employing one or more variable condensers, or a dual section or split stator variable condenser in parallel with one or more sections of the bandspread control as shown at 37. The action of the 40 compensating condensers is to adjust the minimum and maximum capacity of the parallel combination, thereby effectively controlling the tuning range of the bandspread control.

With the compensating control of Fig. 1 the 50 ideal resultant curve C of Fig. 3 may be approached very nearly, as shown by the curve C^{IV} of Fig. 5. In Figs. 3, 4, and 5 the curves A, A' and A^{IV} represent the control action of the high frequency control section 2a of the bandspread control, curves B, B' and B^{IV} represent the control action of the low frequency control section 2b of the band spread control, and since the effects of the two sections 2a and 2b are additive, curves C, C' and C^{IV} represent the resultant action of curves A, B; A', B'; and A^{IV}, B^{IV}, respectively.

The curves of Fig. 5 illustrate the control actions and the resultant action where a split stator or dual section variable condenser 37 is employed as the compensating control for both high and low frequencies in the circuit of Fig. 1.

As may readily be seen from the curves of Fig. 5, the resultant curve C^{IV} is identical with curve C of Fig. 3, but the separate control curves A^{IV} and B^{IV} only approximate curves A and B of Fig. 3, curves A^{IV} and B^{IV} of Fig. 5 most nearly approaching the ideal.

The uses to which the above described control circuits can be put are manifold. For example, it can be applied to various circuits to test lapped

5 quartz blanks for activity and frequency to a close tolerance before they are hand-finished and put in holders. It can be used in receivers where it is desired to have a continuous bandspread of frequency; i. e., one that is constant at any setting of the main tuning control. In conjunction with a local piezo-oscillator (frequency to be determined by type of use) and a receiver, and used in a stable variable frequency generator circuit by "standardizing" at time of use, the circuit can be used to determine the frequency of another signal within a few cycles. This is done by heterodyning the signal emitted by the generator against the unknown signal and detecting the heterodyne beat by audible or electrical or electro-mechanical means and then reading frequency by interpolation from a known standard signal (local piezo oscillator) and the calibration on the dial of the fine tuning control. The circuit can also be used to control the frequency of the emitted radiation of a radio transmitter, allowing the frequency to be varied over a wide range, and yet, by means of the fine tuning control and pre-standardization against a local piezo oscillator or other primary or secondary frequency standard, control the frequency within a few cycles of the desired frequency.

The applications of this invention, as can be seen from the foregoing, are almost limitless. The control circuit can be applied to any device wherein the resonant frequency is desired to be variable. It can be applied to capacity-inductance or capacity-resistance or other impedance-tuned generators or oscillators, to tuned circuits, such as radio frequency, intermediate frequency or audio frequency stages in amplifiers, receivers, filters, etc., or to other tuned circuits wherein any combination of capacity, inductance, resistance, or reactance is used.

Features of my invention shown but not claimed herein are set forth in the parent application, Serial No. 505,048, filed October 5, 1943, for Electron tube apparatus, and my co-pending divisional applications Serial No. 563,383, filed November 14, 1944, for Tuning system, and Serial No. 563,385, filed November 14, 1944, for Selective tuning system.

While I have described my invention in certain of its preferred embodiments I realize that modifications may be made and I intend no limitations upon my invention other than may be imposed by the scope of the appended claims.

What I claim as new and desire to secure by Letters Patent of the United States is as follows:

1. An electrical tuning system comprising in combination with an impedance device, a variable tuning condenser having one side thereof connected with a point on said impedance device, a dual condenser including a central rotor and a pair of variably related capacity areas constituting a pair of condenser sections whose capacities vary simultaneously in the same direction, said rotor being electrically connected with another point of said impedance device, one of the condenser sections of said pair being disposed in series with said variable tuning condenser and the other of the condenser sections of said pair being connected effectively in parallel with the said variable tuning condenser and effectively in parallel with said impedance device, independently adjustable variable capacity means connected in series with each of the condenser sections of said dual condenser, and means connected in shunt with each of the condenser sections of said dual condenser for compensating for the effect-

tiveness of the respective condenser sections at any point in the frequency range of said tuning system.

2. An electrical tuning system comprising in combination with an impedance device, a variable tuning condenser having one side thereof connected with a point on said impedance device, a dual condenser including a central rotor and a pair of variably related capacity areas constituting a pair of condenser sections whose capacities vary simultaneously in the same direction, said rotor being electrically connected with the other end of said impedance device, one of the condenser sections of said pair being disposed in series with said variable tuning condenser and the other of the condenser sections of said pair being connected effectively in parallel with the said variable tuning condenser and effectively in parallel with said impedance device, independently adjustable variable capacity means connected in series with each of the condenser sections of said dual condenser, and a second dual condenser having a central rotor and a pair of variably related capacity areas forming a pair of independent condenser sections, said last mentioned central rotor being electrically connected with said first mentioned central rotor and the last mentioned independent condenser sections being electrically connected in parallel with the aforementioned condenser sections for adjustably compensating for the effectiveness of the respective condenser sections at any point in the frequency range of the tuning system.

3. An electrical tuning system comprising in combination with an impedance device, a variable tuning condenser having one side thereof connected with a point on said impedance device, a dual condenser including a central rotor and a pair of variably related capacity areas constituting a pair of condenser sections whose capacities vary simultaneously in the same direction, said rotor being electrically connected with another point of said impedance device, one of the condenser sections of said pair being disposed in series with said variable tuning condenser and the other of the condenser sections of said pair being connected effectively in parallel with the said variable tuning condenser and effectively in parallel with said impedance device, independently adjustable variable capacity means connected in series with each of the condenser sections of said dual condenser, a second dual condenser having a central rotor and a pair of variably related capacity areas forming a pair of independent condenser sections, said last mentioned central rotor being electrically connected with said first mentioned central rotor, and variable capacity means disposed in series between each of said last mentioned independent condenser sections and the aforementioned condenser sections for adjusting the amount of control said second dual condenser exerts with respect to the first mentioned dual condenser.

GEORGE S. WACHTMAN.
